PISTON RING

Victor F. Zahodiakin, Forest Hills, N. Y.

Application December 13, 1939, Serial No. 309,021

13 Claims. (Cl. 309—44)

This invention relates to improvements in oil rings of the type adapted to be used in pistons. The improved ring of this invention is of particular value for use as an oil ring for the pistons of internal combustion engines but is not limited to this use. It is capable of use, with the same advantages, as the oil ring for the pistons of pumps, steam engines or any installation where it is necessary to prevent the escape of oil along a cylinder wall past a piston.

It has been one of the objects of the present inventor to provide an oil ring for pistons which is adapted to the above uses and which will readily and easily conform to any irregularity in the contour of a cylinder and will, in this respect, be of great value for use in worn cylinders. In other words the general purpose has been to provide an oil flow control ring which will conform to localized irregularities or distortions as well as to general irregularities in the contour of the cylinder wall.

It has been a further object of the present inventor to provide a piston ring which can be made, preferably, from a single strip of metal in an extremely simple manner by forming the basic structure of the complete ring in a single punch press operation whereupon the ring is completed by bending operations performed on this basic structure. The present application is directed to the article, the method being disclosed and claimed in an application copending herewith, now Patent No. 2,339,538.

It has been a further object of the present inventor to provide a ring formed from a flat strip of metal by punching and bending which provides a maximum amount of oil clearance passageway between the top and bottom walls of the ring and through a back wall thereof. Furthermore it has been his object to construct and arrange the metal of the flat strip so that the ring consists of a series of box-like segments opening completely toward the cylinder wall and providing oil clearance passageways in the back wall toward the piston groove. These box-like segments are connected by flexible spring portions permitting compression and expansion of the ring, that is, permitting the sections to move toward and from each other as compression and expansion occur. Thus a ring is provided having the gap, which normally permits expansion and contraction, arranged in minute divisions around the entire circumference of the ring.

One embodiment of the invention may consist of a single strip of metal bent to provide box-like segments open to the side facing the

cylinder wall and having a perforated back wall. Thus these sections appear U-shaped in radial cross section. The sections are integrally connected by spring loops, which loops are disposed between the top and bottom walls of the ring thereby forming spacers and supports across which the walls may slide as the loops flex. It will be seen that the ring is firmly braced against pressures from above and below and is integrally connected at the back so as to prevent buckling of the top and bottom walls when the ring is compressed to the point of closing the minute clearances.

Other advantages of the invention will be more fully apparent from the description of the drawing in which:

Figure 1 is a perspective view showing the completed ring ready for installation in the piston and cylinder.

Figure 2 is a side view of the piston ring shown in Figure 1.

Figure 3 is a fragmentary top plan view of the ring.

Figure 4 is a plan view of a portion of the basic structure of the ring after it has been punched from the flat strip of metal.

Figure 5 is a plan view of the strip of Figure 4 showing the ring partially completed with the spring loops constituted by bending alternate portions of the strip into loops.

Figure 6 is an edge view of Figure 5 more clearly illustrating the loops.

Figure 7 is a view of the strip taken in the same direction as Figure 4, but showing portions of the strip bent into position to form the top and bottom walls of the ring.

Figure 8 is a plan view of Figure 7 further showing the series of bent portions constituting the top and bottom walls.

Figure 9 is a plan view of the strip as it is being bent into circular form by pressing the sections together with their adjacent edges radially disposed.

Referring to the drawing:

45 A flat strip of metal, 10, is punched to provide the basic ring structure shown in Figure 4. This strip of metal is of a length sufficient for forming a single ring when all of the folding and bending operations are completed.

50 Referring to Figure 4, the punching operation provides a number of sections, 11, connected by loop sections, 12. Each of the sections, 11, includes a back panel portion, 13, and top and bottom panels 14, 14. In the punch press operation 55 a large oil clearance opening 15 is punched cen-

trally in the back panel 13 of each section. The end edges 16 of the top and bottom panels are inclined for the reason that later on in the formation adjacent edges of adjacent sections are to be disposed on radial lines (Figure 9).

In the next operation the connecting portions 12 are looped as shown in Figure 6. These loops 17 flexibly connect the sections 11. Obviously these sections will then be closer together.

In the next operation the top and bottom panels 14, 14 are bent down upon the loops by means of which they are slidably supported. The loops are formed with relatively large bights so that the top and bottom panels overhang the loops (Figure 8). Thereafter the sections are pressed closer together accentuating the looped condition of the portions 12 and, as shown in Figure 9, arranging the edges 16 on radial lines. This completes the ring except for heat treating and grinding.

The steel preferably used in the fabrication of this ring has the following approximate analysis: carbon, .45 to .55; manganese, .60 to .90; chrome, .80 to 1.10; and vanadium, .15 to .18. This metal is sufficiently ductile before heat treatment to permit the punch press and bending operations used in the formation of the ring from a single strip of metal.

When the ring is completely formed and set it should be properly treated to provide a ring of the maximum hardness and spring tension. For this purpose it should be heated to approximately 1450 to 1500 degrees Fahrenheit, then quenched in oil and thereafter drawn to reduce brittleness and to obtain the desired hardness. This is accomplished by heating to a temperature of from 600 to 800 degrees Fahrenheit. After this operation the outer periphery of the ring may be ground to provide a ring of the size desired and one having a fine finish.

This ring generates circumferential pressure through the connecting loop portions 17. These loop portions connect the back panels of the respective sections and thus the pressure is exerted through these panels. The tension which the ring usually exerts on the cylinder wall in which the ring is adapted to reciprocate will be easily controlled by initial increase or decrease in the width of the spaces 18 between the sections. Thus the completed ring may be said to consist of box-like sections 19 interconnected by the loops 17. The substantially continuous ground outer edges 20 engage the cylinder wall. The ends of these box-like portions on the outer periphery are entirely open for receiving the oil. The back walls include the large clearance openings 15 which permit rapid return of the oil to the back of the ring. The oil clearance passages are thus quite large and there is no chance of clogging because of carbon deposit. The looped portions make up the sides of the box-like sections and since the panels 14, 14 overhang the loop portions, greater rigidity is achieved. The ring will not collapse and the straight condition of the top and bottom walls is never disturbed. The circumferential expansive and compressive forces merely flex the loops. These forces do not change the positions of the top, bottom and back walls of the box-like structures in any way. The sections constituted by these walls are rigid and non-yielding. The top and bottom walls cannot buckle or bend since they are unitarily attached along the upper and lower edges of the back walls. The forces exerted during the working movements of the ring are conveyed by the loop

portions to the back walls, and not to the top and bottom walls. These walls are merely carried by the back walls and supported by the loops. The portions taking the strains of compressive and expansive forces are the circumferentially disposed back walls and they cannot buckle due to the angular bracing afforded by the top and bottom walls.

In punching the blank (Figure 4) the notches 21 are cut into the back panel on the line of the loop strips 12. Thus when the loops are formed (Figure 8) the loops begin inside the line of the upper and lower panels 14, 14 and are therefore spaced apart at least the width of the spaces 18 at their attached ends 22.

Also it will be noted that the ring may be split as for example at 23 for convenience in assembling it on the piston.

Having described my invention, I claim:

20 1. A flexible piston ring fabricated from a strip of resilient sheet material and consisting of a series of circumferentially arranged bent and folded sections, U-shaped in radial cross section and each providing an open front and a perforated back wall member, and spring loops connecting corresponding wall members of said sections.

20 2. A flexible piston ring fabricated from a strip of resilient sheet steel and consisting of top and bottom wall sections joined by back wall sections and spring loops connecting said back wall sections, said spring loops disposed parallel with the axis of the ring and between the top and bottom walls for supporting said walls.

35 3. A piston ring comprising a series of sections each consisting of top and bottom walls and a back wall, and loops of spring metal connecting the side edges of the adjacent back panels, said loops projected toward the outer periphery of the ring and extending laterally between the top and bottom walls.

45 4. A flexible piston ring formed from sheet metal, said ring including a series of U-shaped sections the arms of which constitute the top and bottom walls of the ring and, loop sections disposed parallel to the axis of the ring, said loop sections having their inner ends formed integrally with the side edges of the base of the U-shaped sections and their looped ends extended outwardly and laterally between the adjacent U-shaped sections whereby the top and bottom walls may slide on the upper and lower edges of the loop sections as the ring compresses or expands.

55 5. A flexible piston ring formed from a strip of resilient sheet material and consisting of a series of circumferentially arranged sections, U-shape in radial cross section and providing open fronts and perforated back walls, and spring loops connecting said sections, said spring loops extending radially between the upper and lower walls of the U-shaped sections and terminating short of the outer periphery of the ring.

65 6. A piston ring, comprising a flexible strip of material bent to provide interconnected U-shaped portions, alternate portions having their arms forming the tops and bottoms of the ring and the other portions disposed radially and parallel to the axis of the ring and providing flexible connections for the first named portions disposed between the arms of the first named portions.

70 7. A piston ring formed from a strip of spring steel and providing a continuous length having radially outwardly projected loops formed there-in and, outward extensions from the upper and

lower edges of the strip intermediate the loops and constituting the top and bottom walls of the ring.

8. A piston ring comprising a series of substantially rectangular enclosures arranged circumferentially, the outer peripheral and inner peripheral ends of the enclosures providing for the flow of oil through the enclosures and, spring means connecting said enclosures and constituting the side walls thereof.

9. A flexible piston ring formed from sheet metal, said ring including a series of U-shaped sections the arms of which constitute the top and bottom walls of the ring and, looped sections disposed parallel to the axis of the ring, said looped sections having their inner ends formed integrally with the side edges of the base of the U-shaped sections, and their looped ends extended outwardly, and said looped ends adapted to lie between adjacent arms of the U-shaped sections whereby the top and bottom walls of adjacent U-shaped sections may slide on the upper and lower edges of the loop as the ring compresses or expands.

10. A self-expanding sheet metal piston ring comprising a central portion having a successive series of spring loops disposed outwardly therefrom at intervals in a generally radial direction, said springs being capable of compressing and expanding in a generally tangential and circumferential direction, a pair of annular cylinder-contacting ribs flanking said central portion, each formed of a multiplicity of closely adjacent cylinder-contacting elements disposed outwardly from said central portion and integral therewith, said cylinder-contacting elements overlapping said spring loops and said spring loops serving also to give support to said cylinder-contacting elements.

11. A self-expanding piston ring formed of sheet metal comprising a central corrugated portion extending around through the entire circumference of the piston ring and having corrugations therein disposed in a generally radial direction (as distinguished from a generally axial

direction) and a multiplicity of cylinder-contacting elements flanking said central corrugated portion and extending throughout the circumference of the ring to form a pair of spaced sectional annular cylinder-contacting ribs, said cylinder-contacting elements being disposed outwardly from said central corrugated portion and adjacent cylinder-contacting elements being so arranged in close proximity to each other as to form a more

5 cylinder-contacting elements being so arranged in close proximity to each other as to form a more or less continuous cylinder-contacting rib; said corrugations tending to expand the piston ring circumferentially and also radially outwardly when the ring is confined to the cylinder diameter.

10 12. A self-expanding piston ring formed of sheet metal comprising a central corrugated portion extending around through the entire circumference of the piston ring and having corrugations formed outwardly thereof in a generally radial direction (as distinguished from a generally axial direction) and a multiplicity of cylinder-contacting elements flanking said central corrugated portion and extending throughout the circumference of the ring to form a pair of spaced sectional annular cylinder-contacting ribs, said cylinder-contacting elements being disposed outwardly from said central corrugated portion and adjacent cylinder-contacting elements being so arranged in close proximity to each other as to form a more or less continuous cylinder-contacting rib; said corrugations tending to expand the piston ring circumferentially and also radially outwardly when the ring is confined to the cylinder diameter, said corrugations serving also to support said cylinder-contacting elements axially.

15 13. As an article of manufacture, a piston ring comprising a strip of resilient sheet material formed at opposite edges with segments extending therefrom, said material being folded transversely of the strip to comprise an annular body in which the folds of material are radial of the ring and at right angles to the segments, said segments formed to comprise circumferential sealing surfaces for the ring.
